UNITED STATES PATENT OFFICE.

ELMER V. GRIGGS, OF WHITE PLAINS, NEW YORK, ASSIGNOR TO WESTERN ELECTRIC COMPANY, INCORPORATED, OF NEW YORK, N. Y., A CORPORATION OF NEW YORK.

TRANSMISSION SYSTEM.

Application filed October 16, 1925. Serial No. 62,722.

This invention relates to transmission systems in which a carrier wave is used for transmitting signals of frequencies within the audible range, and it relates particularly to systems of this kind in which two or more signals of similar frequencies, but differing in phase or intensity are simultaneously translated, transmitted and faithfully reproduced with their original similarities and differences.

Systems of this type have heretofore been used for the purpose of locating sounds with respect to fixed and known points, as in submarine soundings, direction and range finding. They have also been used for the purpose of providing for a realization at the receiving station of the relative locations of various sound sources with respect to one another at the transmitting station, as in binaural transmission over wires (or by radio) of musical programs and incidental sounds for talking movies.

Such systems have in the past possessed a serious drawback in the necessity of using one transmission channel for each of the different versions of the same sound. The spectra of frequencies for radio and wire transmission are necessarily limited and with the rapid growth of this art, it has been found inadvisable to adopt this method of transmission. This is true even in case of radio broadcasting of orchestral programs and the like, in which the sense of location of the various instruments has been found to materially assist in the appreciation of the program by the listener.

Another disadvantage of these systems, when applied to radio systems resides in the fact, that it has so far been necessary to use an antenna with its associated power equipment for each transmission channel, thus necessitating duplication of expensive equipment and doubling the power required to transmit the signals a given distance. Moreover, fading of the different carrier waves to different degree tends to cause a false apparent shift of position of the originating sound sources.

In accordance with the present invention the low frequency signals from two sound translating devices are transmitted as components of a single carrier wave. The carrier is modulated by signals from one device and the upper side band of the resultant wave is selected and impressed upon the transmis-

sion circuit. The same carrier is separately modulated by signals from the other device and the lower side band of the resultant wave is selected and impressed upon the same transmission circuit.

An object of the present invention is to reduce the number of frequency bands required for transmission systems of the type described above, so that the frequency spectrum may be economically utilized.

Another object is to minimize duplication of equipment used in such systems.

A further object is to increase the efficiency with respect to the power output of a transmitting system of that type.

Further features relate to the reduction of cross talk between signals transmitted by such a system.

In order to more fully explain the nature of the invention, its organization and method of operation, it will be described hereinafter as applied to a radio broadcasting system for producing binaural effects. It is to be understood, however, that the invention is not limited to such use nor to the specific details involved, since it may find ready application in various other systems for transmission of sounds, as well as for transmission of light or other physical variations.

The description should be read in conjunction with the attached drawing, which shows diagrammatically one circuit arrangement of a transmitting and a receiving apparatus.

In the diagram are shown two pick-up or translating devices 10 and 11, which may be of the microphonic or other type adapted to broadcasting purposes. These devices may be placed within the field of musical sounds produced, say, by an orchestra, and may be spaced apart in a manner which may be found most suitable for binaural reproduction. The two devices 10 and 11 will thus receive the same sounds from the instruments, but the phase relation and intensity of the sounds received from the individual instruments will depend upon the location of these with respect to the devices 10 and 11.

The low frequency currents produced by the pick-up device 10 and representing one version of the musical sounds pass through a band filter 12 and are impressed upon an amplifier circuit 13.

The currents produced by the pick-up device 11 and representing another version of the musical sounds pass through a band filter 14 and are impressed upon an amplifier circuit 15.

14 and are impressed upon amplifier circuit 15.

The amplifiers 13 and 15 are shown by way of example as including three element vacuum tubes 16 and 17 respectively, the output circuits of which are connected to the respective output circuits of two repeating and modulating tubes 18 and 19, also of the three element vacuum tube type. A low frequency choke coil 20 is included in the common battery lead for the output circuits of tubes 16 and 18, and a low frequency choke coil 21 is similarly provided for tubes 17 and 19.

A high frequency oscillator 22 is connected to the input circuits of modulators 18 and 19, for the purpose of supplying a carrier wave thereto. The oscillator may be of the electron discharge type, such as described in U. S. Patent No. 1,356,763, October 26, 1920 to 20 Hartley.

With the circuit arrangement as shown the carrier wave supplied to the modulator 18 will be subject to the usual repeater action, and will at the same time, be modulated in accordance with the low frequency currents present in the output circuit of amplifier 13.

The carrier wave impressed upon modulator 19 is similarly amplified and modulated in accordance with the low frequency current 30 present in the output circuit of amplifier 15.

For a description of the modulating action here taking place and the part played therein by the impedances 20 and 21, resort may be had to Patent No. 1,537,941, May 19, 1925 to 35 Heising, where a similar system is disclosed in Fig. 2.

As is well known, the high frequency waves resulting from the inter-action between the carrier wave and the speech frequency wave 40 in the modulator tube 18 will be composed of components of the frequency C of the carrier and of the sum and difference frequencies C+S₁ and C-S₁; where S₁ represents the speech frequency in this branch of the system. 45 Other components may be present, but they will not effect the operation of the system so far as concerns the present invention.

The high frequency wave present in the output circuit of modulator 19 will similarly be 50 found to be composed of the frequencies C, C+S₂ and C-S₂, where S₂ represents the speech frequency in this branch of the circuit.

S₁ and S₂ being of the same order of frequencies the side bands produced by combining them with C will, of course, be of the same width.

These two waves are now impressed upon the band filters 23 and 24 respectively, of which one is designed to pass a frequency band 60 corresponding to the upper side band, or sum-frequency component of the present carrier wave; while the other is designed to pass a band corresponding to the lower side band, or difference-frequency component thereof.

Reference may be had to Patent No. 1,227,113,

May 22, 1917 to Campbell, for a description of the design and operation of band filters or selecting network of this type.

Since filter 23 will pass only an upper side band of the modulated wave, and filter 24 will pass only a lower side band, there will be present in the common output circuit 25 of these filters the side bands C+S₁ and C-S₂, and due to the somewhat rounded characteristic at the cut off points of both networks, the bands passed by them will be wide enough to overlap at the carrier frequency, so that enough energy of the carrier C will also be present in circuit 25. Thus the resultant output wave will comprise the above mentioned side bands and an unmodulated component of carrier frequency which serves for detecting purposes at the receiving station.

The purpose of the band filters 12 and 14 in the low frequency or pick up circuits in this embodiment of the invention is to prevent excessive cross talk in the receiving system due to this overlapping of the bands passed by the selecting networks 23 and 24. The low frequency filters 12 and 14 are adapted to cut off as much of the lower frequency of the musical notes or voice, received by pick up devices 10 and 11, respectively, as would be consistent with the desired quality of reproduction, and may, therefore, be designed to 55 pass frequencies between 200 and 5000 cycles.

The side bands impressed upon the filters 23 and 24 will thus have adjacent frequency limits of approximately C+200 and C-200 cycles, which will permit overlapping at the carrier frequency C, and yet be effective in 60 eliminating cross talk in the receiving circuits.

It appears to be desirable, in a system of the type described above, to take precautions to reduce cross talk because of the high frequency commonly used for the carrier in present day broadcasting systems and the consequent comparative lack of sharpness at the cut off points which would be found in band filters, such as 23 and 24. However, due to the similarity of the two signals transmitted, a certain amount of cross talk may 65 very well be permitted.

In wire carrier systems, where the carrier frequency is comparatively low, the band filters, corresponding to 23 and 24 in the drawing, may be designed to cut off very sharply at their limiting frequencies, so that the side bands formed in a manner similar 70 to that described above, will not be likely to overlap. The low frequency filters, corresponding to 12 and 14 above, may therefore in such systems be entirely dispensed with, without giving rise to detrimental cross talk 75 at the receiving station. Energy of the unmodulated carrier frequency may in this case be applied directly to the output circuit corresponding to 25 in the drawing.

Returning now to the system described 80

above the output circuit 25 is connected through amplification equipment 26 to the transmission or antenna circuit 27-28.

The wave transmitted from the antenna 27 consists of an upper side band, a lower side band, and a carrier component. This wave occupies the same width as a single broadcasting channel, but contains the two versions of the original sound. Economy in the utilization of the broadcast spectrum may thus be obtained.

It will readily be seen that this system requires only a single amplification equipment with its power supply, as well as a single antenna for transmitting two signals, as a consequence of which the first cost of equipment and the cost of maintenance are materially reduced.

At the receiving station the transmitted wave is picked up by the receiving antenna 30 and is impressed upon the band filters 31 and 32, which are similar to the filters 23 and 24 respectively. Filter 31 passes the side band C+S₁ and a part of the energy of the carrier frequency C, while filter 32 passes the side band C-S₂ and some energy of carrier frequency C. By means of detector sets 33 and 34 respectively, of any known type, the modulated and unmodulated components are combined to produce the original low frequency waves S₁ and S₂ which are respectively impressed upon the individual receiving elements 35 and 36 of any convenient translating device, such as a head-set 37.

The phase differences and relative intensities of the original signals having been retained throughout, due to the similarity of equipment in the two branches of the system, a striking realization of the distribution of the various sound sources at the transmitting station is conveyed to the listener through his binaural sense.

It should be understood that many other arrangements may be devised for the broadcasting of binaural programs, to which this invention may be applied. However, the particular method of modulation, indicated in the drawing, has the advantage that the modulation taking place in the plate circuit of one tube, for example, 18, will have a negligible effect upon the grid circuit of this tube and will therefore not affect the input circuit of the other tube 19, and conversely the modulation effected in tube 19 will not appreciably affect the input circuit of tube 18. The provision of two separate circuits for connecting oscillator 22 to the respective input circuits of tubes 18 and 19 will still further assist in the successful separation of the signal S₁ and S₂.

What is claimed is:

1. In a carrier system, a method of transmitting signals, which comprises deriving from a single source signal impulses differing

in phase from each other, separately modulating a carrier wave by said differently phased impulses, selecting one side band component of each modulation, and transmitting the selected components over a single channel. 70

2. In a carrier system, a method of transmitting signals which comprises deriving from a single source signal impulses differing from each other, separately modulating a carrier wave by the respective derived impulses, selecting the sum frequency component of one modulation, selecting the difference frequency component of the other modulation and transmitting the selected components over a single channel. 75 80

3. In a carrier system, the method of producing binaural effects, which comprises deriving from a single source signal current impulses differently phased with respect to each other, separately modulating a carrier wave by said de-phased currents, selecting the upper side band component of one modulation, selecting the lower side band component of the other modulation, simultaneously transmitting the selected side bands 90 over a single channel, selecting and detecting said components to produce the de-phased currents, and using said de-phased currents to separately reproduce signals. 95

4. In a carrier system, a method of transmitting signals which comprises receiving two binaurally related versions of an audible signal, and transmitting over a single channel a carrier wave modulated with waves within the same frequency range in accordance with said versions. 100

5. In a carrier system, the method of transmitting signals, which comprises separately modulating a carrier wave by current impulses derived from two translating devices, 105 selecting one side band of one modulation, selecting one side band of the other modulation, simultaneously transmitting the selected side bands over a single channel, selecting and detecting said side bands to independently 110 produce said current impulses. 115

6. A carrier system comprising means for deriving from a single source signal impulses differing in phase from each other, means for separately modulating a carrier wave by said differently phased impulses, means for selecting alternate side band components from said modulations, and means for transmitting the selected components over a single channel. 120

7. A carrier system comprising means for deriving from a single source signal impulses differing from each other, means for separately modulating a carrier wave by the respective derived impulses, means for selecting the sum frequency component of one modulation, means for selecting the difference frequency component of the other modulation, and means for transmitting the selected components over a single channel. 125

8. A carrier system for producing binaural 130

- effects comprising means for deriving from a single source current impulses differently phased with respect to each other, means for separately modulating a carrier wave by said 5 de-phased currents, means for selecting the upper side band component of one modulation, means for selecting the lower side band component of the other modulation, means for simultaneously transmitting the selected 10 side bands, means for selecting and detecting said components to produce the de-phased currents, and separately energizing signal reproducing elements in accordance with said de-phased currents.
- 15 9. A carrier system comprising two translating devices spaced in binaural relation, and means for transmitting over a single channel a carrier wave modulated with waves within the same frequency range in accordance with 20 signals produced simultaneously by said devices.
10. A carrier system comprising two translating devices, means for separately modulating a carrier wave by signals derived from 25 said translating devices, means for selecting the upper side band components of one modulation, means for selecting the lower side band components of the other modulation, means for simultaneously transmitting the selected 30 side bands over a single channel, and means for selecting and detecting said side bands to independently produce said current impulses.
11. In combination a source of carrier energy, means for modulating said carrier energy with waves located within the audio fre- 35
- quency range to produce an upper and a lower side band thereof, the respective side bands representing the same sound differing in phase by an audibly perceptible amount, and means for simultaneously transmitting 40 said two side bands over a single channel.
12. An oscillator producing a carrier wave, two three-element vacuum tube repeaters having their input circuits associated with said oscillator, means associated with their respective output circuits to modulate the carrier wave repeated thereby with two waves within the same frequency range in accordance with a sound wave, as received at two separate positions, and means for selecting and simultaneously transmitting over a single channel two side bands of the modulated carrier representing the two sound versions. 45 50
13. In a carrier receiving system a method of binaural reception of signals, which comprises receiving in a single path a complex wave composed of a carrier wave with two side bands respectively produced by modulation of a single carrier wave with different waves within the same frequency range and 55 representing sound having binaural characteristics, impressing said wave on separate paths selective of specific components thereof, and detecting the selected components to yield currents adapted to reproduce sound waves 60 having the same binaural characteristics as the original sound. 65

In witness whereof, I hereunto subscribe my name this 7th day of October A. D., 1925.
ELMER V. GRIGGS.
